UNITED STATES PATENT OFFICE.

JOHN HALBRITTER, OF BOSTON, MASSACHUSETTS, ASSIGNOR TO WALWORTH MANUFACTURING COMPANY, OF BOSTON, MASSACHUSETTS, A CORPORATION OF MASSACHUSETTS.

METHOD OF MAKING METAL PLUGS.

1,386,106.

Specification of Letters Patent.

Patented Aug. 2, 1921.

Application filed March 30, 1920. Serial No. 370,028.

To all whom it may concern:

Be it known that I, JOHN HALBRITTER, of Boston, in the county of Suffolk and State of Massachusetts, a citizen of the United States, have invented a new and useful Improvement in the Methods of Making Metal Plugs, of which the following is a full, clear, and exact description, reference being had to the accompanying drawings, forming a part 10 of this specification, in explaining its nature.

The present invention relates to a method of making metal plugs having a threaded body adapted to fit within a hole or opening and a head by which the plug may be turned.

Hitherto plugs of this character have been made by casting, the casting afterward being machine-finished. This is a very slow and expensive method and many of the plugs were either misformed or lost during the 20 casting.

The object of the present invention is to do away with casting during the formation of the plug and to make the plug a machine-made proposition. It is found that this may 25 be done by the following method which is described in the light of a plug made of steel.

The method can better be described in the light of the drawings forming a part of this 30 specification, and in which—

Figure 1 is a side elevation of the rod or blank from which the plugs are initially formed.

Fig. 2 is a plan of the blank after the first 35 operation has been performed for making the plug.

Fig. 3 is a plan of the blank after the next operation has been completed.

Fig. 4 is a plan of the uncompleted plug 40 after it has been severed from the blank, and

Fig. 5 is a plan of the finished plug.

Referring to the drawings:

1 represents a rod or blank preferably cylindrical in form and in size conforming to 45 the size of the plug desired to be obtained after the series of operations have been completed for making the plug.

The first operation consists in making an 50 annular cut or incision 2 in the blank or rod. This cut is made at a point removed from the end of the rod by a distance substantially equal to the length of the body of the plug desired to be obtained, 3 representing that portion of the blank forward of the cut, or,

in other words, the unfinished body of the 55 plug.

The annular cut 2 extends lengthwise of the rod a distance slightly less than the length of the head desired to be obtained in the finished plug, that portion 4 of the rod 60 around which the cut is made representing the unfinished head of the plug.

The end portion 3 of the rod or unfinished body of the plug is then externally threaded and thereby finished, 5 representing the 65 threads cut thereon (see Fig. 3). The finished body and unfinished head of the plug is then cut from the rod by an incision 6 made at the inner end of the annular cut 2 and there is accordingly obtained the plug 70 as shown in Fig. 4 provided with an unfinished or circular head and a finished body.

The next operation consists in finishing the head of the plug by squaring or otherwise forming it as may be desired. This is 75 effected by pressure, the head being formed or shaped by an application of force applied laterally thereto. This forming of the head by lateral pressure may be successfully accomplished without disturbing the threads 80 on the body of the plug especially those just adjacent the head, owing to the fact that the head contains less metal measured diametrically than the body and the application of force laterally for forming the head tends 85 only to lengthen it without disturbing the body and threads upon it. In this connection care should be taken that the annular cut 2 initially made in the rod should be so deep or so much metal should be removed 90 that the application of pressure laterally to the head will not disturb the threads on the body. For example, with a $1\frac{3}{8}$ " steel rod a depth of cut of at least $\frac{1}{2}$ " should be made or otherwise the pressure applied to the head 95 will tend to disturb the threads on the body and spoil the plug. After pressing up the head there is obtained the finished plug as shown in Fig. 5.

The series of operations above referred to 100 may be effected in any suitable manner. These operations apart from the pressing up of the head are such that they may be successfully and automatically accomplished upon a turret lathe or better upon a screw 105 machine. The pressing up of the head may be effected by any one of a variety of well known types of presses.

Having thus fully described my invention, I claim and desire to secure by Letters Patent of the United States:—

1. The method of making metal plugs which comprises the incising of a metal rod at a point removed from the end of the rod a distance substantially equal to the length of the body of the plug desired to be obtained whereby forward of said cut there is left a portion of the rod forming the unfinished body of the plug and back of said body a portion of the rod forming the unfinished head of the plug, externally threading the unfinished body of the plug and thereby finishing the same, cutting the then finished body and unfinished head of the plug from the rod, and shaping and thereby finishing the head by application of pressure laterally thereto, the incision initially made in the rod being in such amount as to leave in the unfinished head of the plug such lesser amount of metal than in said finished body of the plug as to avoid the upsetting of the threads on the body of the plug adjacent said head upon the application of lateral pressure for shaping the head as aforesaid.
2. The method of making metal plugs which comprises the incising of a metal rod at a point removed from the end of the rod a distance substantially equal to the length of the body of the plug desired to be obtained whereby forward of said cut there is left a portion of the rod forming the unfinished body of the plug and back of said body a portion of the rod forming the unfinished head of the plug, externally threading the unfinished body of the plug and

thereby finishing the same, cutting the then finished body and unfinished head of the plug from the rod, and shaping and thereby finishing the head by application of pressure laterally thereto, the incision initially made in the rod being in such amount as to leave in the unfinished head of the plug such lesser amount of metal than in said finished body of the plug as to avoid the upsetting of the threads on the body of the plug adjacent said head upon the application of lateral pressure for shaping the head as aforesaid.

3. The method of making metal plugs which comprises the steps of incising a metal blank at a point removed from the end of the blank a distance substantially equal to the length of the body of the plug desired to be obtained whereby forward of said incision there is left a portion of the blank forming the unfinished body of the plug and back of said body a portion of the blank of lesser diameter than the body and forming the unfinished head of the blank, externally threading the unfinished body of the plug and thereby finishing it and shaping and thereby finishing the head by application of pressure laterally thereto.

JOHN HALBRITTER.
